UNITED STATES PATENT OFFICE.

ALVIN D. ALLEN, OF SYRACUSE, NEW YORK.

HANDLE FOR COFFINS, &c.

SPECIFICATION forming part of Letters Patent No. 356,184, dated January 18, 1857.

Application filed November 15, 1856. Serial No. 218,892. (No model.)

To all whom it may concern:

Be it known that I, ALVIN D. ALLEN, of Syracuse, in the county of Onondaga, in the State of New York, have invented new and useful Improvements in Detachable Coffin-Handles, of which the following, taken in connection with the accompanying drawings, is a full, clear, and exact description.

My invention relates to the class of devices termed "detachable coffin-handles," and the object is to provide a compact, simple, and effective attaching plate or plates for securing the handles of coffins or caskets detachably, so that the same handles may be repeatedly used upon burial-caskets and readily removed without unscrewing the plates; and to this end the invention consists in providing two plates, one of which is provided with a groove and screw-holes for securing the same to the coffin or casket, while the other is provided with a tongue fitting in the groove and a spring-stop taking in a recess in the grooved plate, and the said tongue-plate has journaled in lugs formed thereon a handle-support, whereby the grooved plates secured to the casket and tongue-plate, carrying the handle-support, may be readily united by sliding one within the other, and as readily disengaged by sliding the handle-carrying plate out of the grooved plate, all as more particularly hereinafter set forth; and it also consists in the details of construction and arrangement of the parts, as fully described in the specification, and pointed out in the claims.

In specifying my invention, reference is had to the accompanying drawings, in which the same letters of reference are used to indicate identical parts in all figures.

Figure 1 is a side elevation of the invention, showing the back of the plates for attaching the handle to the coffin. Fig. 2 is a top plan, slightly enlarged, showing the two plates in their engaged position. Fig. 3 is a detached view of the tongue-plate carrying the securing-spring. Fig. 4 shows a side elevation, enlarged, of the tongue-plate, handle pivoted to the plate, and the spring for locking the plate to the grooved plate. Fig. 5 is an enlarged detail of the plates with the metal broken away in the grooved plate to show the spring taking in the recess therein for securing the tongue-plate to the grooved plate. Fig. 6 shows an

edge view of the grooved plate. Fig. 7 is a section on line x x , Fig. 8. Fig. 9 shows a reversal in the construction illustrated in Figs. 7 and 8, in which the recess and shoulder 55 for the spring to bear against are formed in the tongue-plate and the spring secured in the grooved plate. Fig. 10 is a further modification, in which a spring-stop takes the place of the flat spring shown in the first form of my 60 invention, the tongue and grooved plates being in section taken on line z z , Fig. 14, for the purpose of showing the construction and arrangement of the spring stop. Fig. 11 is an inverted bottom plan of the tongue-plate of 65 the modified construction illustrated in Fig. 10. Fig. 12 is a section taken on line y y , Fig. 11, illustrating the construction of the parts. Fig. 13 is a top plan of the grooved plate, which is secured to the casket in the modified construction; and Fig. 14 is a similar view of the modified construction provided with the step or recess for the spring-stop. Fig. 15 illustrates a further modification in the spring-stop device for connecting the plate, said view being 70 partly in section and broken away to show the spring-stop device. Fig. 16 is a transverse section of the tongue and dovetail plates, illustrating the modification in the construction of the parts. Fig. 17 is a bottom plan of the 80 tongue-plate; and Figs. 18 and 19 illustrate, respectively, the spring stop device shown in Fig. 15.

A is the handle-support, and B the handle connected to the support in any suitable manner. The said handle may be of any desired design. The handle-support A is connected to the plate a by pivoting the same between the lugs l l , Figs. 2, 3, and 4.

The plate a has a tongue, a' , formed thereon, 90 and a spring, c , secured at c' , Figs. 4 and 5. The plate a constitutes the device for carrying the handle-support, and in order to connect the handle-support and handle B detachably with the coffin I provide the grooved plate b , which 95 is best shown in Fig. 8. The plate b is provided with a groove, b' , extending through from end to end of the plate, and I provide in said groove a beveled recess, terminating in an abrupt shoulder at its deepest extremity, which 100 comes next to the top of the plate, as best shown in Figs. 5 and 7.

The through-groove b' may be a dovetail groove, as illustrated in Figs. 2 and 6, and the plate b is provided with screw-holes for the attaching-screws, which secure the plate to the coffin.

5 The plate b is preferably secured to the coffin with the abrupt shoulder d' of the recess d upward, and the handle-carrying plate a , provided with the tongue a' and spring c , is 10 slid into the groove b of the plate downward, the two plates interlocking when the spring c takes in the recess d . When the plates are thus interlocked, the spring c bears against the shoulder d' in the recess d . Consequently when 15 it is desired to raise the casket by the handles B the tongue-plate a is firmly united or interlocked with the plate b against upward pressure, which is resisted by the shoulder d' of the recess d , and the coffin or casket may be raised 20 by the handle as readily as though the handle were permanently secured thereto, and when it is desired to detach the handles it is simply necessary to press downward, so as to withdraw the spring c from the beveled recess, when 25 the two plates a b slide apart, enabling the operator to remove the handle without unscrewing the plate from the coffin or casket.

It will be observed that the two plates are united by sliding the handle-carrying plate a 30 into the plate b , secured to the coffin, from the top until the spring c takes in the recess d , the shoulder d' of which prevents the withdrawal of the plate a when the coffin is lifted by the handles, and that the plates are disengaged by 35 sliding the plate a downward on b through the bottom of the groove b' , which movement is permitted by the groove b' , extending through from top to bottom or end to end of the plate b , and the beveled recess d allows the spring c 40 to be withdrawn from below as the plate a is pushed downward to remove the handle.

If desired, the plate b may be provided with the raised beads e and the plate a , provided with a corresponding depression, e' , Fig. 5, 45 which also interlock and aid in holding the plates a b securely together.

The example of my invention which I have just described is my preferred plan of constructing the same; but the construction and 50 arrangement of the parts may be considerably changed and modified without departing from the principle of my invention. Hence I do not restrict myself to the precise construction and arrangement illustrated and described.

55 At Fig. 9 I have illustrated a reversal of the arrangement of the recess d and spring c , the spring c being secured to the plate b , and the recess d , with the shoulder d' , being formed in the tongue-plate a . In this case the abrupt shoulder d' is at the lower end of the handle-carrying plate a , and the operation of the parts is precisely the same as in the previously-described form of my invention.

At Fig. 10 of the drawings I have illustrated 65 a further modification in the construction and

arrangement of the interlocking plates. In this case the plates slide transversely, the plate b , instead of having the groove b' running vertically through the plate, has the said groove running transversely, and the plates interlock 70 horizontally. The recess d in this case may consist of a circular seat or step, formed, preferably, in the plate b , and the spring-stop c may consist of a spring-actuated pin, as shown in Figs. 10 and 12, which takes in the step or recess d and 75 securely locks the plates.

At Fig. 15 a still further modification is illustrated, in which the spring-stop c is formed in the shape of an eccentric, and a spiral S , is inserted between the plate a and the handle-support A , to prevent the handle-support 80 A from bearing against the trigger of the spring-stop c when the handle-support A is depressed so as to collide with the spring-stop c . The spring-stop c rocks on its pivot, clearing 85 the recess d , when the plates may be detached, as above described.

Figs. 16 and 17 show a still further modification in the form and construction of the tongue and groove in the plates a and b , as 90 illustrated, and which will be readily understood upon reference to the drawings.

The essential characteristics of my invention reside in the combination of the handle-carrying plate and the plate secured to the 95 coffin, one of the plates being provided with a groove and the other with a tongue, and a spring-stop secured to one of the plates, taking in the recess in the other, whereby the plates interlock by sliding one into the other, 100 and are readily detached in the manner described.

Having thus fully described my invention, what I claim as new, and desire to secure by Letters Patent, is—

105 1. A detachable handle for coffins and like articles, comprising a plate secured to the coffin, a plate carrying the handle-support, one of the plates being provided with a groove and the other with a tongue, and a spring-stop secured to one of the plates, taking in a recess in the other plate when the plates are interlocked by sliding one into the other, substantially as and for the purpose set forth.

110 2. The combination of the plate a , having the handle-support A secured thereto, and a tongue, a' , with the grooved plate b , having the beveled recess d , in the shoulder d' , at one end thereof, and the spring c , substantially as and for the purpose set forth.

115 In testimony whereof I have hereunto signed my name, in the presence of two attesting witnesses, at Syracuse, in the county of Onondaga, in the State of New York, this 10th day of November, 1886.

ALVIN D. ALLEN.
